UNITED STATES PATENT OFFICE.

DANIEL P. GOSLINE, OF BOSTON, MASSACHUSETTS.

HUMIDIFIER.

Application filed June 20, 1923. Serial No. 646,730.

My invention is an improvement upon that class of humidifiers commonly used to produce and maintain in textile or other mills some well known and desirable atmospheric conditions, where uniformity of saturation and diffusion are essential elements. Too much moisture in parts of a room caused by oversaturation is quite as detrimental to good results as no moisture at all; for over-saturation and consequent deposit of moisture on stock or machinery often cause heavy losses. Humidifiers as ordinarily used forcibly eject moisture into the atmosphere of the room without providing for its diffusion and regardless of the fact that air can only carry in suspension a definite amount of moisture; hence supersaturation in the neighborhood of the humidifier and a consequent deposit of moisture will necessarily result.

My invention comprises a specially constructed atomizer requiring no water pressure and a very low air pressure and is constructed to provide in addition a sufficient volume of continually flowing unsaturated air which is thrown from below into the atomized stream, supporting and diffusing it through the room, thus preventing oversaturation in the vicinity of the apparatus. As a result of the use of my apparatus the finely atomized water or other liquid will directly impinge on a moving current of air and be more or less taken up by it and carried away to change the condition of the atmosphere. The air and water are not brought in contact in the machine but outside of it and are easily controlled so that any desired condition of the atmosphere can be controlled by controlling the air-moving elements of the machine.

My invention will be understood by reference to the drawings in which it is shown in its preferred form.

Figure 1 is a side elevation of a machine embodying my invention.

Fig. 2 is a plan thereof with part of the casing broken away showing the air pump, etc.

Fig. 3 is a section on line 3-3 of Fig. 1.

Fig. 4 is an end elevation.

Fig. 5 is a section on line 5-5 of Fig. 7.

Fig. 6 is an enlarged cross section taken through the atomizer and showing the oil separator and air drum and its connection, and

Fig. 7 is a longitudinal section of the machine.

1 is a casing comprising side walls, a flooring and a cover to keep out dust and the like. 200 is a flooring on which is supported an electric motor 3 of ordinary construction having a shaft 4 on which is mounted the rotor of the air pump 5 which is also of any usual construction and is supported on the flooring 201. A blower fan 6 is mounted on the outer end of the shaft 4. On the floor of the casing is the movable pan 2 of proper size to catch any oil drippings.

The purpose of the pump is to supply air to the atomizers and this it does through the pipe 7 on the top of which is mounted a pressure gauge 8. An elbow 9 connects this pipe with an enlargement thereof 10 from which a pipe 11, made preferably in sections as shown, runs into a drum 12. As it is desirable that the air supplied to the pump 5 shall be as clean as possible it is supplied by the pipe 275 shown in elevation in Fig. 3, its upper end curving over as shown in dotted lines in Figs. 1 and 7, and if necessary provided with a strainer of some suitable kind.

13 is an oil cup which is connected by the pipe 14 to lubricate the air pump. Provision is made to prevent any lubricant from reaching the atomizers by the pipe enlargement 10 in which the air may expand slightly and drop the lubricant, which the air may carry from the pump, such lubricant being led off by the pipe 19 controlled by pet cock 191.

As a certain amount of lubricant may still be retained in the air or air passage, provision is made to eliminate it by two baffles 20 and 21 contained in the drum 12 to which the enlargement 10 is connected by the pipe 11. From the pipe 11 the air passing into the drum impinges on the baffle 20 the lower edge of which is notched, then through the notches and up between 20 and 21 leaving most of the lubricant which it may carry behind it. The baffle 21 is provided with a hooked edge or wiper 23 and collects any remaining lubricant from the air so that the air is in condition to pass through the nozzle 22 of the atomizer without fouling it. This lubricant separated from the air collects in the bottom of the drum.

24, 24 are closures for the ends of the

drum which may be removed when necessary to drain the oil from the drum. These closures also serve as a means of supporting the drum on two brackets 25, 25 which are 5 mounted on the water tank 26.

27, 27 are small tapering pipes each leading down into the water, stopping preferably at some point between the bottom of the tank 26 and the normal water level 29, the upper 10 end of each being provided with a nozzle 28.

In practice I prefer to attach the upper end of each water pipe 27 to a carrier 41 which as shown is hung on the pipe 221 which carries the nozzle 22 of the atomizer.

15 Each nozzle proper 22 is formed in a cap 220 which screws onto the end of the pipe 221 extending from the drum 12. The carrier 41 has an upward extension 42 having an opening therethrough, through which

20 passes the pipe 221. In a passage 43 through this extension is located a spring 44 which is adjustably held in the passage by a screw plug 45, the upper end of this spring resting against the under surface of the pipe

25 221. Through the upper portion of this extension passes a set screw 46 the lower end of which rests on the top of the pipe 221 so that the pipe is held between the spring 44 and the screw 46 and within certain limits 30 the position of the nozzle 22 and tip of the pipe 27 may be adjusted with relation to each other to secure the desired spray. The tank 26 may be filled and kept full of water in any common way either automatically or 35 by hand. I have shown two atomizers one near each end of the device, but any length of drum may be used with a corresponding number of atomizers and fans.

As stated above, the tendency of sprays 40 is to fall to the floor. To prevent this I provide a blower having a specially constructed air-directing baffle which not only delivers air to receive and absorb the sprays, but also spreads them in such a way as to 45 produce complete diffusion through the room. This device which I will call an air distributor is designed first, to correct the spiral air delivery common to all such blowers; second, to diffuse and deflect the air 50 without impeding its velocity so that it will drive into the atomized sprays mixing therewith and assimilating some of their moisture, and by its force diffusing a current of properly conditioned air substantially 55 throughout the room.

This air distributor is located in the end of the casing 1 in front of the blower fan 6 which is set into an opening in the wall 60 which divides the front end of the casing 30 from the rear end in which is located the pump and the motor. In front of the blower fan 6 is located a box 40, the side walls of which slant inward toward the periphery of the fan, and within this box 65 are mounted a series of vertical baffle plates

32 and 33 all held in place by rods 34. The bottom of the spaces between these baffles is formed by a series of curved plates 400 attached at their lower and inner ends to the floor of the box 40 and projecting forward and upward. One side of each plate being higher than the other and registering with the adjacent side of the plate next it so as to have the effect of a curved continuous flooring extending upwardly from one 70 side of the box 40 to the other, but broken by the baffles 32 and 33 and the baffle plates all swing to cause the blast of air to be guided upwardly and lift the atomized jets thrown from the nozzles. The front of the 75 box 40 is somewhat in rear of the front wall of the tank 26 which is preferably slanting so as to direct the air which strikes it from the blower and box upwardly.

It will be noted that one baffle 33 of the 80 baffle plates extends nearer than the others 32 to the face of the fan. This divides the current of air into two substantially equal blasts. The location of this baffle off the centre of the fan secures better results than 90 if it be located in a plane with the axis of the fan. It has been found that in its rotation a fan of this kind tends to throw the air not out in lines parallel to its axis but to one side of the axis in a swirl so that 95 the air will be crowded over to one side of the box, say to the left side of the box (see Fig. 4). By using a baffle like 33 which approaches the fan quite closely and is located to the left of the axis of the fan 100 looking from the front, the crowding of the air referred to is prevented to a large degree and by locating a number of baffles 32, 33 as shown the swirling of the air is 105 prevented and it is thrown out from the fan in approximately a straight line until it is deflected upwardly by the floor against the slanting wall of the end of the tank so that it is given an upward and outward direction which carries it into the spray from 110 below, supporting the moisture and carrying it along, thus diffusing it throughout the room.

This same result may be otherwise secured, and I do not mean to limit my invention to the exact construction shown.

What I claim as my invention is:—

1. A humidifier comprising an air nozzle discharging air under pressure, a liquid nozzle and a liquid tank and connections between said liquid nozzle and said tank, said air nozzle being located with relation to said liquid nozzle whereby the air from said air nozzle will draw up and atomize liquid from said tank through said liquid nozzle 120 and will mingle with said atomized liquid, in combination with means comprising a blower located below said liquid nozzle and means whereby the blast from said blower will be directed to and discharged under said 130

atomized liquid whereby said atomized liquid will be carried by said blast and diffused.

2. A humidifier comprising an air nozzle discharging air under pressure, a liquid nozzle and a liquid tank located below them having a front slanting wall and connections between said liquid nozzle and said tank, said air nozzle being located with relation to said liquid nozzle whereby the air from said air nozzle will draw up liquid from said tank through said liquid nozzle and atomize it, in combination with means comprising a blower located below said tank and means co-operating with said blower adapted to drive the air from said blower against the outer surface of said slanting wall whereby it will strike said atomized liquid and tend to drive it upward.
3. A humidifier comprising an air nozzle discharging air under pressure, a liquid nozzle, a tank and connections between said liquid nozzle and said tank, said air nozzle and said liquid nozzle being located with relation to each other whereby the air from said air nozzle will draw up and atomize the liquid from said tank and will diffuse said atomized liquid, in combination with means comprising a blower located below the tank and connections whereby the air from said blower will be directed upward and toward

said atomized liquid and will further cause the diffusion of said atomized liquid.

4. A humidifier comprising a compressed air delivery mechanism and a water delivery mechanism located in relation thereto whereby a spray will be delivered by the action of the air from said air nozzle, in combination with means located below the spray delivery whereby said spray will be diffused laterally and upwardly from said humidifier, said means comprising a blower fan, and means located in front of said fan to receive and direct upwardly the air coming from said fan.

5. A humidifier comprising an air delivery mechanism comprising an air nozzle discharging air under pressure and a water delivery mechanism located in relation thereto whereby a spray will be delivered by the action of the air from said air nozzle, in combination with means whereby said spray will be diffused laterally and upwardly from said humidifier, said means comprising a blower fan and means located in front of said fan to receive and direct the air coming from said fan, said last-named means comprising baffles and an upwardly curved flooring located between said baffles to cooperate therewith in diffusing the air from said fan.

DANIEL P. GOSLINE.
